BENJAMIN R. BARBER, OF JACKSONVILLE, FLORIDA

METHOD OF MAKING LATCHES FOR RAIL SWITCHES AND BLANKS FOR THE SAME

Application filed April 1, 1932. Serial No. 602,541.

This invention is directed to an improvement in latches for rail switches, particularly of the type described in my copending application filed September 17, 1931, Serial 5 #563,425.

The primary object of the present invention is the provision of sheet metal sections, with the parts particularly constructed for interrelation to form the stand of the latch, with 10 a particular view of closing the interior thereof against the admission of snow and the like, which under adverse atmospheric conditions will freeze in the interior of the stand and prevent proper operation of the latch.

15 Ordinarily, stands of this type are constructed of cast metal which, to provide for the assemblage of the various parts, necessarily present openings which, in the use of the latch in climates open to snow and the like, 20 at certain periods of the year, suffer the disadvantage of being rendered inoperative or difficult to actuate under extreme weather conditions. With the stand constructed according to the present invention, the interior 25 is substantially closed against the admission of the elements and thus to a material extent the latch is prevented from being rendered inoperative under such conditions.

30 A particular and important object of the invention is the provision of two similar blanks initially formed and divided so as to permit the ready making up of the stand and consequent sealing of the interior of the same against the elements to a substantial extent.

35 The invention is illustrated in the accompanying drawing, wherein:—

Figure 1 is a view of the blank.

Figure 2 is a perspective view of the switch stand made up from the blank.

40 Figure 3 is a longitudinal section of the latch.

The blank is made up of sheet metal of appropriate gauge and formed to provide a body portion 1 having an upper section 2 constituting one-half of the top of the stand, the upper section being bendable along the lines 3 and 4 and having a terminal section 5 for cooperating with the similar section of the other blank, as will later appear. The 45 body is formed at the lower end with an ex-

tension 6 bendable along the line 7 to provide a foot. The forward edge of the body immediately above the foot 6 is extended at 8 and above the extension and throughout the remaining length of the similar edge of the body 55 there is provided an extension 9 slightly spaced from the extension 8 and bendable along the lines 10 and 11 to present an outstanding section 12 to cooperate with the similar section of the other blank.

The edge of the body of the wall opposite the section 9 is formed with a section 13 extended beyond the edge of the body and divided therefrom at the upper edge, as at 14, and bendable along the line 15, the body being extended at 16 below and beyond the extension 13 and divided from the latter on the line 17. The foot extension 6 of the body is extended beyond the end of the projection 16, as at 18, and this portion of the blank is extended upwardly through the full height of the blank, providing a portion 19, the free outer edge of which is upwardly and inwardly inclined, this extension 19 being bendable along the line 20 at the end of the section 16 70 and also bendable along a parallel line 21 forwardly of the line of bend 20 and providing a narrow strip 22 approximately half the width of the frame. 75

The line of bend 20 throughout the extreme upper portion of the section 19 forms a line of division by cutting out a section from the upper edge of the extension 19, the line of cut being in the line of fold 21 on the one side and on a line 23 inclined to the line of fold 21 on the other side, thus forming a substantially V-shaped cut out portion. A section 24 of rectangular form is cut out from the foot 6 underlying the strip 22.

In forming the blank into the frame, two 90 blanks are similarly formed or shaped in the following manner: The upper portion of the body 1 is folded downward at right angles on the line of fold 3 and then upward at right angles on the line of fold 4, presenting upstanding sections 5 which are substantially in the mid-line of the longitudinal plane of the body. The rear section 9 of each blank 95 is then bent inwardly at right angles on the line of fold 10 and then outwardly at right 100

angles on the line of fold 11, presenting sections 12 in substantially the mid-line of the longitudinal plane of the body and extending rearwardly therefrom. The sections 13, 5 which at the lower end are divided from the body extension 16, are then bent inwardly, these sections approximating one-half the width of the body. The section 19 is then turned inwardly on the line of fold 20 and 10 then outwardly on the line of fold 21, thus presenting the sections 22 at right angles to the longitudinal plane of the body and in spaced relation to the sections 13 and arranging the sections 19 for that portion beyond 15 the line of fold 21 about midway of the longitudinal plane of the body. The foot piece 6 is likewise turned out at right angles to the body.

In order to permit this movement of the 20 foot piece 18, it is divided from the foot piece 6 along the line forming the forward line of cut of the section 24, and the foot piece 6 is extended below and in spaced relation to the foot piece 18, as at 25, providing, when 25 the foot pieces are turned upwardly, a recess 26 for the fastening of the frame as a whole to a tie or other support, a similar cut out portion 27 being formed in the foot piece 6 for like purpose.

30 If the blanks thus formed are arranged in opposition, the body 1 will be spaced apart a distance approximating twice the distance between the lines of fold 3 and 4 of the section 2. Between the walls of the body and 35 spaced from the upper wall defined by the blank folds as described are arranged angle pieces 28, the vertical sections of which bear against the body and the horizontal ledges 29 of which provide a support for the latch 40 proper. These angle iron sections are bolted in place by through rivets 30, and the proximate edges of the ledges 29 are spaced apart to provide for the operation of the latch lever.

45 The latch comprises a metallic body 31 having a latch nose 32, the upper surface of which is inclined downwardly and forwardly and the rear of the body formed with a longitudinal bore 33 extending approximately half 50 the length of the body, and the bottom wall is formed with a recess 34. The latch slides on the ledges 29 of the respective angle bars and immediately above the upper edges of the sections 13.

55 When the blanks are assembled, the contacting portions 5 and 12 are bolted together at 35 and 36 and the sections 19 are bolted together at 37, thus securing the frame parts in cooperating relation. An angle lever 38 60 is pivotally supported at 39 on a pivot bar extending through the opposed bodies 1, this lever projecting rearwardly between the extensions 8 of the blanks and underlying the edges of the sections 12 which form a limit 65 for the upward movement of the lever.

Secured to each side of the extended portion of the lever are plates 40, the forward portions of which present plate sections 42 and the rear portions of which present angle sections 43, with the vertical flanges in line with the plate sections 42. Two such plates 40 are secured to the extended portion of the lever on opposite sides thereof by rivets 44, in which position the horizontal ledges of the angle portion 43 of the plates form a broad 70 tread for the lever, while the plate sections 42 snugly and slidably embrace the connected sections 12 of the blank. The blank sections 19 when formed for association in the frame provide an upright abutment, between which and the proximate edges of the body the switch lever to be locked is to be positioned. 80

To insure the entrance of the switch lever into the channel between the abutment and the body proper, the upper edges of the sections 22 of each blank, when the blanks are formed in frame-designing relation, are bent outwardly into line with the inclined edge 23 of the cut out portion at the upper end of the section 19. This provides an inclined 85 face 45 for guiding the switch lever into position. A spring 46 is arranged to overlie the angle plates 28 and bear between the form sections 9 at one end and the inner end of the bore 33 of the latch bolt, the spring functioning to serve to maintain the latch projected, in which, as indicated in Figure 3, it forms a limit for the upward movement of the switch lever when in the channel between the abutment and the body 1. The 90 plate sections 42 and the meeting sections 12 of the blanks are preferably formed with openings 47 adapted to register when the latch lever is at its upward limit of movement, that is, in the position in which the latch is fully 95 projected by the spring 46. These openings 47 when in register provide for the reception of an ordinary lock to prevent operation of the device to release the switch lever.

As described, the stand is made up of two 100 blanks integrally formed and shaped for bending to provide the necessary parts of the stand. Of course, the meeting edges of the inturned portions forming the transverse walls may, if desired, be welded or otherwise 105 secured together, though it is quite apparent that through the arrangement described, the parts when associated and secured as indicated substantially close the frame against the admission of the elements. This is the essential 110 purpose of the invention, for with the frame thus protected, the locking latch is little liable to be rendered inoperative incident to the freezing of snow or rain on the interior 115 of the body or the collection of snow therein. The blanks provide a simple, convenient 120 means of assembling the body and form a rigid wear-resisting structure which permits 125 access to the interior conveniently by separating the means for connecting the blanks. 130

The operation of the switch stand, for both locking and releasing the switch lever, is quite apparent from the disclosure, as the mere movement of the switch lever into the stand serves to force the latch rearwardly due to the inclined upper face of the nose of the latch, and when the switch lever rides beneath the latch, the spring operates to automatically move the latch to lever-locking position. When it is desired to release the switch lever, depression on the free end of the latch lever withdraws the latch to permit free upward movement of the switch lever.

Having thus described the invention, what is claimed as new, is:—

1. A blank for the fabrication of a latch stand, comprising a metallic section foldable to form one-half of the body portion of the stand and an outstanding securing lip, the section being divided vertically from the upper edge but not extending to the lower edge, said divided portions being folded relative to each other to form right-angled sections to provide an abutment.
2. A blank for the fabrication of a latch stand, comprising a metallic section having a cut-out portion near one edge, a foldable portion on one margin of the cut-out portion a similar foldable portion at the opposite edge of the section, said foldable portions defining a body portion of the stand, the opposite part of the cut-out portion being divided vertically and folded relatively into right angled portions to provide an abutment.
3. A process of forming a latch stand from two duplicate blanks, each blank being foldable on predetermined lines to form a hollow body with upper, front, and rear walls, the blanks being cut out in advance of the folded portions defining the front walls, with the portion in advance of the cut-out divided vertically to provide separate portions united at the lower end, the separate portions being relatively folded on right-angled planes to provide an abutment with a broad face spaced from the front wall of the body.
4. A process of forming a latch stand from two duplicate blanks, each blank being cut out adjacent one edge, the edges of the main portion of the blank being folded to provide the end walls of a hollow body portion, the advance part of the cut-out portion being divided vertically and the separate parts folded, one in the plane of the body and the other at right angles thereto.

In testimony whereof I affix my signature.
BENJAMIN R. BARBER.
